(57) **CLAIM**

The ornamental design for a walking stick convertable into a seat, as shown and described.

DESCRIPTION

FIG. 1 is a front perspective view of a walking stick convertable into a seat, in a non converted state, showing our design.

FIG. 2 is a back and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a perspective view of the walking stick convertable into a seat which is disassembled into two parts.

FIG. 10 is a perspective view of the walking stick convertable into a seat, which is converted into a seat wherein legs and seat fully extended.

FIG. 11 is an enlarged view of an area labeled 11 in FIG. 1; and,

FIG. 12 is an enlarged view of an area labeled 12 in FIG. 1. The broken lines depict portions of the article that form no part of the claimed design.

1 Claim, 12 Drawing Sheets
